(57) **CLAIM**

The ornamental design for a computer USB flash drive housing, as shown.

DESCRIPTION

FIG. 1 is a top view of a computer USB flash drive housing showing my new design;

FIG. 2 is a front view thereof;

FIG. 3 is a left end view thereof;

FIG. 4 is a right end view thereof;

FIG. 5 is a front, right end isometric view thereof; and,

FIG. 6 is a top, left end isometric view thereof.

The shading shown on the drawings is for the purpose of indicating areas of light and shadow, and does not represent color or color contrast.

The claimed computer USB flash drive housing is used to hold and protect a USB flash memory device, and could be used by persons, or in situations, where such protection would be desirable.

The claimed design features a hexagonal cross section throughout, with the exception of one end having material removed to reduce the thickness, and that same end having a countersunk hole made through it.
